CLAIM

The ornamental design for a portable blender jar with handle as shown and described.

DESCRIPTION

FIG. 1 is a front view of a portable blender jar with handle, showing the new design;

FIG. 2 is a rear view thereof;

FIG. 3 is a side view thereof;

FIG. 4 is a top view thereof;

FIG. 5 is a bottom view thereof;

FIG. 6 is a rear perspective view thereof;

FIG. 7 is a front perspective view thereof; and,

FIG. 8 is a front perspective view thereof, shown in environmental use.

The broken lines in the drawings are for showing portions of the portable blender jar with handle that form no part of the claimed design. The broken lines forming a portable blender base in FIG. 8 are for the purpose of illustrating environment and form no part of the claimed design.
